UNITED STATES PATENT OFFICE.

LEWIS L. SCOTT, OF ST. LOUIS, MISSOURI.

COMBUSTION SYSTEM.

1,323,916.

Specification of Letters Patent. Patented Dec. 2, 1919.

Application filed May 26, 1919. Serial No. 299,715.

To all whom it may concern:

Be it known that I, LEWIS L. SCOTT, a citizen of the United States, residing in the city of St. Louis and State of Missouri, have 5 invented new and useful Improvements in Combustion Systems, of which the following is a specification.

My invention relates to the burning of heavy oils which are practically non-volatile 10 at normal temperature, and has for its general object to provide a novel system for effecting the ignition and combustion of such oils, for automatically controlling the operation of the igniting means, both as relates to the duration of operation thereof 15 and to the automatic stopping and starting of the same after the system has been placed in operation, and for automatically controlling the operation of the system according 20 to combustion conditions.

The invention has for its further object to combine in such a system a vapor generator for volatilizing the oil to be burned and to provide for initially vaporizing and igniting 25 the oil at the vapor burner by spraying said oil, igniting said spray, and directing the ignited spray over a burner located beneath a vaporizing coil supplying the oil thereto, whereby the oil will be first volatilized and 30 then be ignited at the burner by said ignited spray, after which the latter is automatically cut off, and combustion proceeds under the automatic action of the vapor burner.

In the accompanying drawing, the view is 35 a diagrammatic representation of my improved combustion system, the vapor burner being shown substantially in plan view with reference to the parts with which it is connected to more clearly illustrate the construction, and the system as a whole being shown combined with a steam generating device.

Referring now to the drawing, the numeral 1 indicates the coils of a semi-flash 45 steam generator having a water inlet 2 and a steam outlet 3. The coils are inclosed in a heat insulating inclosure 4, in the bottom of which is located a hollow burner 5 provided with openings 6 in its top. Located 50 over the burner is a fuel vaporizing coil 7, provided with a fuel-nozzle 8, which is directed into an air opening 9, entering the side of the burner 5. The other end of the pipe constituting the vaporizing coil 7 is 55 connected to and communicates with a valve casing 10. A fuel pipe 11 leads from the

fuel tank 12 to the valve casing 10. Within the valve casing 10 is a valve 10^a for controlling the supply of fuel to the vaporizing coil 7. The numeral 13 indicates an air compressor on the opposite sides of which are the usual check valves 14 and 15, and which is connected to an air tank 16, which is adapted to be supplied with air to a pressure of, say, 100 lbs. The numeral 17 indicates a reducing valve in a pipe 18 which leads from the air tank to the top of the fuel tank 12. The valve 17 is adapted to reduce the pressure of the air to, say, 50 lbs. Leading from the bottom of the fuel tank 12 is a second fuel pipe 19 in the length of which is inserted a float valve 20, from which leads a pipe having a fuel nozzle 21. Leading from the air tank 16 is an air pipe 22^a in the length of which is inserted a reducing valve 22 which is adapted to reduce the air pressure to, say, 2 lbs. Beyond the reducing valve 22, the pipe 22^a is supplied with a valve 23 operated by a solenoid 23^a, and beyond this latter valve said pipe is provided with an air nozzle 24. The fuel nozzle 21 and air nozzle 24 are mounted in coöperative relation within an ignition chamber 25 provided with a spark plug 26, the relation of the parts being such that when air passes under pressure from the nozzle 24 it will aspirate and atomize oil from the nozzle 21 and the atomized oil will be ignited by the spark plug 26. The numeral 27 indicates an electric motor which operates the fan of 90 a blower 28, with which blower is connected a pipe 29, which surrounds the ignition chamber 25 and enters the generator casing 4 above the burner 5. The numeral 30^a indicates the primary winding of a spark coil, 95 and the numeral 30 the secondary winding thereof, from which latter a wire 31 leads to the spark plug 26, said wire being grounded at its other end as indicated at 32. The numeral 33 indicates a battery, and 34 a switch 100 provided in the length of the positive wire 35 leading from said battery. The numeral 36 indicates a Bourdon tube which is connected by means of a steam pipe 37 with the generator coils 1. The numeral 38 indicates 105 an insulated screw-contact with which operates a spring-held lever 39 which is connected to and operated by the Bourdon tube 36. The positive wire 35 is electrically connected with the lever 39. A wire 40 leads 110 from the said screw 38 to one side of the motor 27. The numeral 41 indicates a solenoid

having a core 42 projecting from one end thereof, and at its other end being provided with a piston 43 working within a cylinder 44, which is provided in its end with a small 5 opening 45 to time the operation of the piston 43. Surrounding the core 42, and located between the solenoid 41 and a contact arm 47 carried by the core, is a coil spring 46. The contact arm 47 is adapted to be 10 moved over an insulated electric contact plate 48 and to be moved off of said plate to break contact therewith by the movement of the core 42. On the other end of the stem of the valve 10^a is a head 49, adapted 15 to be engaged by the inner end of the core 42, and located between said head and the valve casing 10 is a coil spring 50, which operates to return the valve 10^a to its seat when the core 42 moves away from the head 20 49. Leading from the negative side of the battery 33 is a wire 51 which is connected by a branch wire to the solenoid 41 and to the contact plate 48. The primary winding 30^a is connected at one end to the wire 40 25 and at its other end, by a wire 52, to the cylinder 44 which, of course, is of metal so that a circuit may be completed through said cylinder, the piston 43, core 42, contact arm 47 and contact plate 48. A branch wire 30 leads from wire 40 to the solenoid 41. A wire 54 leads from the wire 52 to one end of the solenoid 23^a and a wire 55 leads from the other end of said solenoid to the other side of the motor.

35 The air compressor 13 in practice would be operated from the motor 27, but to save illustration, I have indicated the same as being separately operated, as by a belt 56, which could be run from a separate motor.

40 The operation is as follows:

The air tank 16 having been supplied with compressed air by operating the air compressor 13, and the switch 34 closed, the motor 27 will be placed in operation. The 45 solenoid 23^a will be energized to open the valve 23 to allow compressed air to escape from the nozzle 24 and aspirate oil from the nozzle 21, and the spark plug 26 will cause the ignition of the sprayed fuel. At 50 the same time, the fan in the blower 28 will cause air to be blown through the pipe 29 to mix with the ignited spray to cause complete combustion and thus heat the vaporizing coil 7. The solenoid 41 will also be energized to move the core 42 to unseat the valve 10^a and allow oil to pass through the pipe 11 and valve casing 10 to the vaporizing coil 7, in which it will be vaporized by the heat of the ignited spray, and passing 55 out through the nozzle 8, will be mixed with air at the opening 9 and escaping upward through the openings 6 in the burner 5 will be ignited by the ignited spray of fuel projected from the pipe 29 over the burner 5.

60 65 The movement of the core 42 also operates to

move the contact arm 47 in contact with and over the plate 48 and eventually to move said arm off of said plate, in which position it is shown in the drawing, whereby the circuit to the solenoid 23^a, motor 27 and spark coil 26 is broken, the supply of sprayed fuel stopped and the spark plug 46 cut out. It will be understood that when the solenoid 23^a is cut out, the valve 23 closes, and hence no oil can be aspirated from the nozzle 21. 70 The movement of the contact arm 47 is timed by the size of the opening 45 in the cylinder 44 which, according to its size, will relieve the vacuum tended to be created by the movement of the piston 43, with greater 80 or less speed. This retarding of the movement of the contact arm 47 is to insure that the various operations above described leading to the supply and ignition of the sprayed fuel and heating of the vaporizing coil 7 shall have occurred before the valve 10^a is opened to permit the flow of oil to said coil, and further to insure combustion occurring at the burner as a result of these operations before the spark-plug and motor 90 are cut out by breaking the contact between arm 47 and plate 48. After the device is placed in operation, as described, the oil in the coil 7 is vaporized by the heat of combustion occurring at the burner 5 in the well 95 known manner. As combustion proceeds, steam is generated in the steam coils 1, and pressure created, which is reflected in the Bourdon tube 36. When a given pre-determined degree of pressure is reached, the 100 Bourdon tube 36 will operate to move the lever 39 out of contact with the screw 38, thereby breaking the circuit to the solenoid 41, and permitting the spring 46 to move the core 42 out of contact with the head 49 105 so that the valve 10^a will be moved by the spring 50 to its seat to cut off the supply of oil to the coil 7. In this movement the contact arm 47 will be carried over the contact plate 48 and toward the opposite end thereof. 110 When the pressure of steam falls to, or below, the critical pressure, the contact between the lever 39 and screw 38 will be renewed, the motor 27 placed in circuit with the battery, and the operation of the system 115 above described be automatically repeated.

When the arm 47 moves over the contact 48 under the pressure of spring 46, which occurs when the circuit is broken by the Bourdon tube, as just described, neither the 120 motor 27, solenoid 23^a or spark plug 26 will be operated, as the circuit including these devices will also be broken by the movement of the lever 39 effected by the Bourdon tube.

I claim:

1. In a combustion system in combination with a vapor burner and means for supplying oil thereto to be vaporized and burned, means for spraying and electrically igniting the spray of a separate body of oil 130

- and projecting the ignited spray in proximity to said burner to produce vaporization and ignition of the oil supplied to the burner, and means for automatically cutting off the supply of sprayed fuel after combustion of the vaporized oil at the burner has started. 5
2. In a combustion system, in combination with a vapor burner comprising a vaporizing coil, means for supplying oil to said coil to be vaporized and burned, means for spraying and electrically igniting the spray of a separate body of oil and projecting the ignited spray over said coil to vaporize oil 10 therein and ignites the resultant vapor, and means for automatically cutting off the supply of sprayed fuel after combustion of the vaporized oil at the burner has commenced. 15
- 20 3. In a combustion system in combination with a burner, a vaporizing coil located above and having a feed-nozzle for supplying vaporized oil to the burner, a source of oil for said coil, means for spraying and electrically igniting the spray of a separate body of the oil and projecting the ignited spray over said burner and about said coil to produce vaporization of the oil in said coil and ignition of the vapor thereof at 25 the burner, and means for automatically cutting off the supply of sprayed fuel after combustion of the vaporized oil at the burner has started.
4. In a combustion system in combination 30 with a vapor burner and means for supplying oil thereto to be vaporized and burned, means for spraying a separate body of said oil and projecting it in proximity to said burner, an electric device for igniting the sprayed fuel, whereby the latter will cause vaporization and ignition of the oil at the burner, a blower for supplying air to the ignited spray to promote complete combustion, a motor for driving said blower, an 35 electric circuit including said motor and ignition device, means for automatically breaking the circuit of said motor and ignition device after combustion of the vaporized oil at the burner has started, and automatic means for stopping the supply of fuel to be sprayed when the said circuit is broken. 40
5. In a combustion system, in combination 45 with a vapor burner and means for supplying oil thereto to be vaporized and burned, an electrically operated valve controlling the supply of fuel to the burner, means for spraying a separate body of the oil and projecting it in proximity to said burner, an electric device for igniting the sprayed oil to produce vaporization and ignition of the oil at the burner, an electrically-operated valve controlling the supply of oil to be sprayed, electric circuits including the electrical operators of said valves and said igni- 50
- tion device, means for retarding the operation of the valve controlling the supply of oil to the burner, means for electrically cutting out the electrical operator of the valve controlling the supply of oil to be sprayed, 70 and said ignition device, after combustion of the vaporized oil at the burner is started. 75
6. In a combustion system, in combination with a vapor burner and means for supplying oil thereto to be vaporized and burned, a solenoid-operated valve controlling the supply of fuel to the burner, means for spraying a separate body of the oil and projecting it in proximity to said burner, an electric device for igniting the sprayed oil to produce vaporization and ignition of the oil at the burner, a solenoid-operated valve controlling the supply of oil to be sprayed, electric circuits including the solenoid of said valves and said ignition device, 80 means for retarding the operation by its solenoid of the valve controlling the supply of oil to the burner, and means for automatically cutting out the solenoid of the valve controlling the supply of oil to be sprayed, and said ignition device, after combustion of the vaporized oil at the burner has started. 85
7. In a combustion system, in combination 90 with a vapor burner and a pipe for supplying oil thereto to be vaporized and burned, a spring-pressed valve in said pipe normally closing the same against the feed of fuel to the burner, a solenoid for operating said valve to open it, means for spraying a separate body of the oil and projecting it in proximity to said burner, an electric device for igniting the sprayed oil to produce vaporization and ignition of the oil at the burner, a valve controlling the supply of oil 95 to be sprayed, a solenoid for operating said valve, electric circuits including said solenoids and said ignition device, means for retarding the operation of the solenoid operating the valve controlling the supply of oil to the burner, and means operated by said solenoid for automatically cutting out said ignition device and the solenoid of the valve controlling the supply of oil to be sprayed, after combustion of the vaporized oil at the burner has started. 100
8. In a combustion system, in combination 105 with a vapor burner and a pipe for supplying oil thereto to be vaporized and burned, a valve normally closing said pipe, a solenoid having a core adapted to operate said valve to open the same, means for spraying a separate body of the oil and projecting it in proximity to said burner, an electric device for igniting the sprayed oil to produce vaporization and ignition of the oil at the burner, a solenoid-operated valve controlling the supply of oil to be sprayed, electric circuits including the solenoids of said valves, means for retarding the move- 110
- 115
- 120
- 125
- 130

- ment of the solenoid core operating the valve controlling the supply of oil to the burner, a contact in the circuit of the ignition device and of the solenoid operating 5 the valve controlling the supply of fuel to be sprayed, and a contact-member carried by the core of the first-named solenoid and adapted to be moved in engagement with and over said contact and then out of en- 10 gagement therewith to break the circuit to the ignition device and the second-named solenoid and to permit the valve operated by the latter to close, after combustion of the vaporized oil at the burner has started.
- 15 9. In a combustion system, in combination with a vapor burner and means for supplying oil thereto to be vaporized and burned, a solenoid-operated valve controlling the supply of fuel to the burner, means for spraying a separate body of the oil and projecting it in proximity to said burner, an electric device for igniting the sprayed oil to produce vaporization and ignition of the oil at the burner, a solenoid-operated valve 20 controlling the supply of oil to be sprayed, electric circuits including the solenoids of said valves and said ignition device, means for automatically cutting out said ignition device and the solenoid of the valve con- 25 trolling the supply of oil to be sprayed, after combustion of the vaporized oil at the burner has started, a heat absorbing medium located above said burner, and means re- 30 sponsive to changes in conditions in the heat absorbing medium for automatically mak- 35 ing and breaking said electric circuits.
10. In a combustion system, in combination with a vapor burner, means for spraying and igniting a separate body of oil and 40 projecting the ignited spray in proximity to said burner to provide a vaporizing heat thereat and a source of ignition, means for supplying oil to the burner in timed re- 45 lation to the action of the ignited spray, whereby the oil so supplied will be vapor- 45 ized and ignited at the burner, and means for automatically cutting off the supply of

sprayed fuel after combustion of the vaporized oil at the burner has started.

11. In a combustion system, in combination with a vapor burner and means for supplying oil thereto to be vaporized and burned, mechanism controlling the supply of fuel to the burner, means for spraying a separate body of oil and projecting it in proximity to said burner, an igniting device for igniting the sprayed oil to produce a vaporizing heat and source of ignition for the oil at the burner, mechanism controlling the supply of oil to be sprayed, means for retarding the feeding operation of the mechanism controlling the supply of oil to the burner in relation to the feeding operation of the mechanism controlling the supply of oil to be sprayed, and means for effecting 60 automatic action of said latter mechanism to cut off the supply of oil to be sprayed after combustion of the vaporized oil at the burner has started.

12. In a combustion system, in combination with a vapor burner and means for supplying oil thereto to be vaporized and burned, mechanism controlling the supply of fuel to the burner, means for spraying a separate body of oil and projecting it in proximity to said burner, an igniting device for igniting the sprayed oil to produce a vaporizing heat and source of ignition for the oil at the burner, common controlling means for the supply of oil to be sprayed 80 and said igniting device, means for retarding the feeding operation of the mechanism controlling the supply of oil to the burner in relation to the production of said ignited spray, and means for effecting automatic 85 action of said common controlling means to cut off the supply of oil to be sprayed and to stop the action of said ignited means after combustion of the vaporized oil at the burner has started.

In testimony whereof, I have hereunto set my hand.

LEWIS L. SCOTT.
